United States Patent Office

Des. 226,905
Patented May 15, 1973

226,905

MUFFLER

Robert F. Buckalew and John D. Owens, both of
1859 Blake Ave., Los Angeles, Calif. 90039

Filed July 8, 1971, Ser. No. 160,998

Term of patent 14 years

Int. Cl. D12—16
U.S. Cl. D14—6 D

Fig. 1

Fig. 2

Fig. 3

Fig. 4

Fig. 5

FIG. 1 is a perspective view of a muffler showing our new design;

FIG. 2 is a top plan view thereof;

FIG. 3 is a side elevational view thereof;

FIG. 4 is an end view thereof; and

FIG. 5 is an end view of the muffler opposite to its end shown in FIG. 4.

We claim:

The ornamental design for a muffler, substantially as shown.
